ARCHERY PACKAGE

Harold G. Paynton, Sr., 39 Clark St., Manasquan, N.J.

Filed Mar. 26, 1959, Ser. No. 802,121

10 Claims. (Cl. 206—45.34)

The present invention relates generally to an improved multi-purpose package, and in particular it relates to an improved package for a bow, arrows and accessory equipment.

It is conventional to package bows and arrows separately, in disposable receptacles which serve no purpose other than that of a temporary protective cover to facilitate the storage, shipping and sale of the bows and arrows. A quiver is generally a necessary accessory in the use of a bow and arrows, for keeping the arrows at hand prior to their use. Thus, there are normally sold at the same time a bow, arrows and a quiver, all of which are usually separately packaged in disposable containers or wrapping material, which increase the cost of the combination while greatly detracting from the convenience in handling same.

It is, therefore, a principal object of the present invention to provide an improved multi-purpose package.

Another object of the present invention is to provide an improved multi-purpose receptacle enclosing a bow and arrows.

Still another object of the present invention is to provide an improved multi-purpose receptacle enclosing a bow and arrow, which receptacle is quickly and easily convertible for use as a quiver.

A further object of the present invention is to provide an improved multi-purpose package of the above nature characterized by simplicity in the formation thereof, its low cost and ease of use.

The above and other objects of the present invention will become apparent from a reading of the following description, taken in conjunction with the accompanying drawing, wherein:

Figure 1 is a front perspective view of an improved multi-purpose package embodying the present invention;

Figure 2 is a top perspective view of a sheet employed in constructing the improved package;

Figure 3 is an exploded perspective view of the casing or receptacle;

Figure 4 is a sectional view taken along line 4—4 in Figure 1;

Figure 5 is a perspective view of a quiver formed from the improved package;

Figure 6 is an enlarged fragmentary sectional view of the quiver support loop assembly;

Figure 7 is a perspective view of the support loop and mounting band structure;

Figure 8 is an exploded perspective view of another form of casing according to the present invention; and

Figure 9 is a transverse sectional view thereof, similar to Figure 4.

In a sense, the present invention contemplates the provision of an improved multi-purpose package of the character described comprising a hollow cylindrical casing including a longitudinally extending tubular member formed of a severable material and end walls closing said tubular member, a bow, arrows and associated archery equipment located in and extending longitudinally of said

casing and a loop member affixed to the wall of said tubular member between the ends thereof.

According to one form of the present invention, the tubular member is formed of a coiled sheet of organic thermoplastic material, the longitudinal borders of which are in overlapping relationship. The end walls are defined by discs having upstanding lips and nesting in the opposite ends of the tubular member and secured thereto by suitable fasteners. Located substantially intermediate the ends of the tubular member are a pair of longitudinally spaced, pressure-sensitive adhesive tapes which encircle the tubular member. There are provided a pair of loops, end portions of which are fastened to the respective tapes and sandwiched between the tapes and the tube wall. A bow, a supply of arrows and, optionally, additional archery accessories may be located in the tubular member. Thus, the package may be opened and access to the contents thereof afforded by severing the tubular wall along one or more peripheral lines between the tapes to divide the casing into a pair of quivers which may then be carried or worn on the person by way of the loops, and to provide, as desired, an arm guard.

Referring now to the drawing and partially to Figures 1 through 7 thereof, which illustrate one embodiment of the present invention, reference numeral 10 generally designates an improved package comprising a casing 12 which contains a bow 14, and a plurality of arrows 16, which are longitudinally arranged in the package. Casing 12 includes an elongated tubular member 18 of circular cross-section and walls 20 closing the ends of the tubular member 18. Tubular member 18 is formed of a rectangular sheet 22 of flexible self-supporting material, preferably a transparent organic thermoplastic material such as cellulose acetate, polystyrene, Saran, nylon or the like, and may have impressed therein a pair of longitudinally-spaced, parallel, transversely extending lines of weakness or score lines 24 which are located substantially intermediate the ends of sheet 22. Lines 24, 24 may be merely imprinted on the surface of the sheet. A pair of transversely aligned openings 23 are formed in sheet 22 adjacent opposite longitudinal edges thereof between score lines 24. Sheet 22 is coiled about a longitudinal axis, and the borders thereof are brought into overlapping abutment to form tube 18.

In order to maintain sheet 22 in its tubular configuration, there is provided a pair of flexible bands 26 of adhesive tape having coatings 28 of a pressure sensitive adhesive on their underfaces, the bands being preferably formed of an organic thermoplastic material such as nylon or the like. A loop 30 is formed of a band of woven cloth or other suitable material by folding the band along its medial transverse axis and bringing ends 32 thereof in superposition. Superposed band ends 32 are located across the adhesive-carrying face of tape 26, extending transversely thereof, and are secured to tape 26 by clinched staples 34. Bands 26 encircle tubular member 18 at longitudinally-spaced, peripheral areas located longitudinally outwardly of and adjacent to lines 24. Bands 26 extend across the exposed longitudinal edge of sheet 22 and the face 28 thereof firmly adheres to the outer face of coiled sheet 22 to maintain it in the form of tubular member 18. Sandwiched and embraced between the tape 26 and the wall of the tubular member 18 are the loop ends 32, loops 30 being each inwardly longitudinally directed.

Each of end walls 20 may be formed of a light gauge sheet metal and includes a disc shaped base portion 36 and an upstanding peripheral flange or lip 38. It should be noted that the lip 38 may be advantageously formed of a material other than metal, such as cardboard, plastic material, or the like. Walls 20 are nested in the ends of the tubular member 18, lips 38 being out-

wardly directed and abutting the inner face of the tube 18. Securing end walls 20 to tubular member 18 are a plurality of clinched staples or other suitable fasteners engaging lips 38 and the wall of the tubular member 18. The packaging is preferably effected by assembling tubular member 18, loop carrying tapes 26 and one of the end walls 20, leaving the opposite end of tubular member 18 open. The bow and arrows 14 and 16, and, if desired, an arm band or string, or other archery accessories, are inserted through the open end of tubular member 18 and the remaining end wall 20 applied and affixed thereto as foresaid to enclose the contents within the container thus formed.

In opening and employing the improved multi-purpose package, the tubular member 18 is severed along lines 12 by employing a sharp instrument such as a knife, razor or the like. The end sections 42 and intermediate section 44 are then separated and the contents of the package removed. The end sections 42 each define a quiver, as illustrated in Figure 5 of the drawing, which may be used in the conventional manner. Moreover, the intermediate section 44, which can be readily uncoiled, may be employed as an arm or wrist guard in the well known manner by passing a band or string through one or both openings 23 and employing the band or string as securing means.

The sheet 22 may be colorless or colored, transparent or opaque and may be suitably decorated and imprinted in any desirable manner. Furthermore, the longitudinal overlapping borders of the sheet 18 may be additionally secured to each other, if desired, by heat sealing, a longitudinally extending adhesive tape, or other fastening arrangement.

The embodiment of the present invention, illustrated in Figures 8 and 9 of the drawings, differs from that above described principally in that the casing member 48 is formed of an extruded thermoplastic tube, and in other details. In addition to instructions and other legends, there is imprinted or formed on the tubular casing member 48, a pair of longitudinally-spaced, encircling cut guide lines or lines of weakness 50, located substantially intermediate the ends of tubular member 48, and a guide line 52 extending longitudinally of tubular member 48 between lines 50. Additionally, circle or dot guides 54, 54 may be imprinted or impressed on opposite sides of guide line 52, to locate the position of openings which can readily be made through the material through which a band or string may be passed so that this medial portion of tubular member 48 can serve as an arm or wrist band. The end walls 20, and bands 26 and loops 30 are assembled and the packaging of the bows and arrows as in the earlier embodiment. The package device is employed in the manner previously set forth. The intermediate section delineated by the lines 50 may be longitudinally slit and employed as an arm guard as desired.

While there have been illustrated and described preferred embodiments of the present invention, it is apparent that numerous alterations, omissions and additions may be made without departing from the spirit thereof.

I claim:

1. A multi-purpose package comprising an elongated hollow cylindrical casing of transparent severable material, end walls permanently closing said casing, a bow and arrows located in and extending longitudinally of the casing and trapped therewithin by the end walls, an elongated loop member one end of which is affixed to a wall of the casing adjacent the center thereof the other end of the loop being free and closer to an end thereof, and a line of demarcation about the casing between the loop member and the other end thereof whereby, on severance of the casing portions along the line of demarcation, that portion between the line of

severance and the first end referred to may be suspended by the said loop.

2. A multi-purpose package as in claim 1, including a second elongated loop member affixed by one end thereof to the casing wall adjacent the center thereof and closer to the other end of the cylinder, the other end of the loop being free including an additional line of demarcation about the casing between said additional loop and the one end of the casing, whereby, on severance of the casing portions through the said additional line of demarcation, that portion of the casing between the said additional line of severance and the said other end of the casing may be suspended by the said additional loop.

15 3. A multi-purpose package as in claim 2, and including a line of demarcation extending lengthwise of the casing between the two first-referred to lines of demarcation, whereby, on severance of the casing portions along the three lines of demarcation there will be provided two arrow quivers and a wrist guard.

20 4. An improved multi-purpose package of the character described, comprising an elongated tubular member defined by a coiled sheet of flexible, severable material having overlapping longitudinally extending borders, end walls secured to and permanently closing said tubular member, maintaining the tubular shape thereof at least adjacent the end walls, a bow and arrows located in and extending longitudinally of said tubular member, a band permanently secured to and encircling said tubular member between the ends thereof, maintaining the tubular shape thereof, and a lengthwise extending loop secured by an end thereof, to said band.

25 5. An improved multi-purpose package of the character described, comprising an elongated tubular member defined by a coiled sheet of flexible, severable material having overlapping longitudinally extending borders, end walls closing said tubular member, a bow and arrows located in and extending longitudinally of said tubular member, a band of pressure sensitive adhesive tape encircling said tubular member substantially intermediate the ends thereof and adherent thereto and a loop having an end portion sandwiched between said tape and the wall of said tubular member.

30 45 6. A package as in claim 5, in which the tape secures the longitudinally extending borders of the coiled sheet in overlapping relationship and the end portion of the loop.

50 7. An improved multi-purpose package of the character described, comprising an elongated tubular member defined by a coiled sheet of flexible organic thermoplastic material having overlapping longitudinally extending borders, walls closing the ends of said tubular member, a bow and arrows located in and extending longitudinally of said tubular member, a pair of longitudinally spaced peripherally extending bands of pressure sensitive tape encircling said tubular member substantially intermediate the ends thereof and adherent thereto, and a pair of loops each having an end portion sandwiched between a respective tape and the wall of said tubular member.

55 60 8. An improved multi-purpose package of the character described, comprising an elongated tubular member defined by a coiled sheet of a flexible organic thermoplastic material having overlapping longitudinally extending borders, a circular wall having an upstanding peripheral lip nested in each of the ends of said tubular member, fastening members securing said peripheral lip to the wall of said tubular member, a bow and arrows located in and extending longitudinally of said tubular member, a pair of longitudinally spaced, pressure-sensitive adhesive tapes encircling said tubular member substantially intermediate the ends thereof and a pair of loops each having an end portion sandwiched between a respective adhesive tape and the wall of said tubular member.

9. A package as in claim 8, including cut guide lines adjacent the tapes and inwardly thereof, dividing the tubular member into a center section and two end sections.

10. A package as in claim 8, including cut guide lines adjacent the tapes and inwardly thereof, and an opening through the sheet, substantially in the center thereof, adjacent each border of the overlapped sheet whereby, on severance of the coiled sheet through the cut guide lines, an arrow storing quiver is realized from each end-closed

section and an arm encircling guard is realized from the center section.
